UNITED STATES PATENT OFFICE

JACK SAVOY, OF GLENMORA, LOUISIANA

RAZOR STROP STERILIZER

Application filed September 22, 1930. Serial No. 483,475.

My invention relates to a razor strop sterilizer, more particularly to a sterilizer adapted to sterilize a razor strop of the kind composed of one or two long strips of leather or other similar substance.

It is a well known scientific fact that razor strops are prolific sources of infection, especially when they are used in public barber shops. Heretofore it has been customary to 10 hang or secure the razor strop to be used at some convenient point near the barber's chair, so that it could be readily accessible to the barber to strop his razor while he was shaving a customer; no provision ever being 15 made to sterilize the razor strop while it was so attached. The strop was used over and over again to sharpen the razor used to shave several persons, without ever sterilizing the razor strop. By this method of using the 20 razor strop, the strop was most of the time exposed to the germ and dust laden atmosphere of the barber shop. The strop was also exposed to excessive moisture on damp days, such exposure being injurious to a 25 razor strop.

The objects of my invention are: first, to provide a practical and efficient device to sterilize razor strops of the kind described; second, to provide a razor strop sterilizer 30 having means to secure or anchor the strop while the strop is being used and also provided with means to automatically return the strop, after use, to the sterilizing chamber of the sterilizer, where the strop may be 35 sterilized without loss of time on the part of the operator; third, to provide in a sterilizer means adapted to serve as a sanitary container in which the razor strop may be protected, when the strop is not in use, from 40 exposure to dust, disease germs and excessively damp atmosphere; fourth, to provide a novelly constructed apparatus of this class, which is simple, economical of construction, durable, practical, easily installed for use, 45 and indispensable to the art of sanitary barbersing.

With these and other objects in view, as will appear hereinafter, my invention consists of certain novel features of construction, 50 combination and arrangement of parts and

portions as will be hereinafter described in detail and particularly set forth in the appended claims, reference being had to the accompanying drawings and to the characters of reference thereon, which form a part 55 of this specification, in which:

Figure 1 is a perspective view of a sterilizer embodying my invention, showing the sterilizer when the razor strop is being sterilized.

Figure 2 is a perspective view of the same, showing the sterilizer when the razor strop is being held ready for use.

Figure 3 is a side view of Figure 1, partially in section, showing details of construction.

Figure 4 is a front view of Figure 1, partially in section, showing further details of construction.

Figure 5 is a sectional view of a portion 70 of the sterilizer, showing positions of certain parts when the strop is extended for use.

Like characters of reference refer to similar parts and portions throughout the several views of the drawings.

My invention comprises a hollow case 1, preferably cylindrical in shape and made of metal. The case is secured to a barber's cabinet or other suitable support by means of screws and the lugs 2. The chamber 3 serves 80 as the sterilizing chamber. Secured to the case 1 is a detachable receptacle 4, made preferably of glass, for the purpose of holding suitable and necessary sterilizing chemicals. The opening in the receptacle 4 is in communication with the chamber 3, so as to admit 85 the vapors from the sterilizing chemicals to enter the chamber 3. Inside of the case 1 is a revolvably mounted drum 5, made preferably of metal. At each end of the drum is fixed a disc 6.

The drum 5 is adapted to revolve around the stationary shaft 7. The ends of the shaft 7 are fixed to the case 1. Positioned around the shaft 7 is a helical spring 8. One end of the spring 8 is secured to the shaft 7 90 and the other end is secured to the drum 5, so that when the drum 5 is revolved a tension is produced on the spring 8. The opening 9 is to admit the strop which is to be sterilized and used in conjunction with the sterilizer. 100

The snap ring 10 is secured to the drum 5 and is used to attach the razor strop. The razor strop 11 is positioned in the sterilizer as shown in Figure 3, having the strop secured to the snap ring 10. The drum 5 is of such a dimension that the outside surface of it receives nearly the entire length of the strop at a single winding of the strop around the drum. When it is desired to use the strop for stropping a razor, the strop is manually pulled outward as shown in Figure 2. This pulling of the strop causes the drum 5 to revolve and the razor strop 11 to unwind, the drum and strop assuming the position shown in Figure 5. Revolving the drum in the above manner causes a tension on the spring 8, so that when the strop is released after use, it is automatically returned to the sterilizer, the strop assuming the position shown in Figures 1 and 3. The stop 12 prevents the winding action of the drum and spring to pull the entire length of the strop into the sterilizer chamber. The stop 12 has a recess in it to admit the connecting link of the strop so that the drum can be revolved freely inside the case 1 during the winding of the strop around the drum. The stop 12 is in close proximity to the inside wall of the case 1, so that when the stop comes in contact with the strop as shown in Figure 3 the drum cannot revolve further. The drum 5 is made of perforated metal, so as to admit the sterilizing vapors to the surface of the strop which is in contact with the drum. The openings 13 admit the sterilizing vapors to the inside of the drum 5.

It is obvious from the foregoing description that the sterilizer embodying my invention is a time saver and an indispensable device for perfect sanitation in the use of a razor strop. When the strop is not in use, it is being exposed to the sterilizing vapors in the sterilizing chamber. Much valuable time is saved because it is unnecessary to detach the razor strop from the sterilizer when one desires to use the strop. When the strop is not in use the opening 9 is practically closed with the protruding end of the razor strop, as shown in Figure 1, thus avoiding excessive escape of the sterilizing vapors from the sterilizer. It is to be understood that it is not necessary to sterilize the entire length of the strop. It is only necessary to sterilize that portion of the strop which contacts with the razor.

It is to be understood that the form of my invention herein shown and described is to be taken as a preferred embodiment of the same and that various changes in the shape, size, and arrangement of parts, may be resorted to, which do not depart from the spirit of my invention, or the scope of the subjoined claim.

Having thus described my invention, what I claim is:

65 In a razor strop sterilizer, the combination

of a sterilizing case, means to secure the said case to a supporting element, a sterilizing medium container detachably secured to said case and in communication with the inside of said case, an opening in the said case through which to admit a razor strop into the said case, a revolvably mounted drum inside of said case, said drum being adapted to wind upon it a razor strop, a spring for rotating said drum to wind up the razor strop, a stop mounted on the said drum and adapted to contact the razor strop and to stop the rotating of said drum at such a point to prevent the winding of the entire length of the razor strop and so as to leave the portion of the razor strop having the hand hold protruding through the opening in the said case.

In testimony whereof I affix my signature.

JACK SAVOY.
